ELECTROLYTIC RECORDING PAPER CONTAINING A SEQUESTRING AGENT

Robert S. Ives, Lexington, Mass., assignor to
Milton Alden, Needham, Mass.

No Drawing. Filed June 11, 1963, Ser. No. 286,951
10 Claims. (Cl. 204—2)

ABSTRACT OF THE DISCLOSURE

Electrochemical recording material consisting of a support impregnated with a water solution containing an organic lake former, an electrolyte and a chelating or sequestering agent to form colorless complexes with stray recording metal ions in non-recording parts of the support. 15

This invention relates to electrolytic facsimile recording and more particularly to an electrochemical recording paper which is more stable in storage and which produces a record of improved definition. 20

Electrolytic recording by passing a modulated electric current through an electrochemical recording paper to produce marks on the paper in accordance with the current is well-known in the facsimile art. One type of paper utilized in such recording has been impregnated with a water solution containing an electrolyte and an organic lake-former which combines with electrode metal ions to form a colored lake on the paper. These recording papers have been used commercially but have given rise to a 25 number of problems and limitations. Such papers after impregnation and particularly after recording, have not been as stable in storage as is desirable and the definition of the record on such paper has been limited. This limited definition is due in part to the fact that the background of the record tends to discolor with time and also to the fact that the recording marks have tendency to "trail" behind the electrode after the current has stopped and to bleed laterally on the paper from the point of recording. The principal object of this invention is to provide electrolytic recording material of the above type which is more stable in storage and which will provide a record with improved definition. 35

In accordance with this invention, the improved electrolytic recording material, for recording with a lake-forming metal electrode, comprises a support impregnated with a water solution containing an organic lake-former, an electrolyte, and a chelating or sequestering agent, said agent retaining stray recording metal ions in colorless form at non-recording parts of the support. Amino carboxylic acid sequestering agents and particularly amino polycarboxylic acids are preferred. Suitable materials include water-soluble salts of ethylenediaminetetraacetic acid (EDTA), and of N-hydroxyethylethylenediaminetriacetic acid. 50

It is believed that the discoloration of the background of the recorded material is to a substantial degree caused by small amounts of metal lake-forming ions which either migrate in a record or are deposited in non-recording portions of the record as it moves between the electrodes. Similarly, it is believed that the trailing of the mark behind the electrode after the recording current has ceased is due to small amounts of the metal ions combining to form a lake either by migration to the support or by mechanical transfer from the record to the electrode and back again to the support. Such trailing is particularly noticeable with highly sensitive organic lake-formers. Both phenomena are substantially reduced with corresponding improvement in the record by the inclusion of chelates according to this invention which complex with such stray metal lake-forming ions to form colorless complexes at non-recording points of the record. 55

2

This invention may be better understood by reference to the following examples:

Example 1

	Grams
Methylene disalicylic acid (MDA)	9
Potassium nitrate	9
Sodium hydroxide	2.25
Versenol 120 (0.5%)	0.6
Water to make 100 cc.	

Versenol 120 is the trademark of the Dow Chemical Co. for a concentrated water solution of the trisodium salt of N-hydroxyethylethylenediaminetriacetic acid. 10

Example 2

	Grams
MDA	9
KC1	9
NaOH	2.25
Sequestrene 30A	0.6
Water to make 100 cc.	

Sequestrene 30A is the trade name of the Geigy Co. for a 39% aqueous solution of tetrasodium ethylenediaminetetraacetate. 20

Example 3

	Grams
MDA	9
KC1	9
NaOH	2.25
Cheeloxy B-14	0.6
Water to make 100 cc.	

Cheeloxy B-14 is a trade name of the Antara Chemical Co. for a 41% aqueous solution of a mixture of soluble salts of amino carboxylic acids. 30

Example 4

	Grams
Tannic acid	140
NaCl	120
Sequestrene Na-2	1.25
Water to make 2 pints.	

Sequestrene Na-2 is the trademark for a solution of salts of amino polycarboxylic acids by the Alrose Chemical Co. 45

Example 5

	Grams
Catechol	450
K nitrate	910
Oxalic acid	36
Thiourea	18
NaH ₂ PO ₄ · H ₂ O	18
Nullapon Fe-12	14
Water to make 2 gal.	

Nullapon Fe-12 is a trademark of the General Dyestuff Corp. for amino polycarboxylic acid salt solutions. 55

Example 6

	Grams
Protocatechuic acid	150
KNO ₃	800
Thiourea	100
Permakleer OH ¹	10.5
Water to make 2 gal.	

¹ Permakleer OH is the trade name for amino polycarboxylic acid chelating agent solutions made by the Refined Products Corp. 60

In the above examples the MDA, tannic acid, catechol and pyrocatechol are all organic lake-formers which combine with the metal electrode ions to form a colored lake. 70

The potassium chloride, and sodium chloride are electrolytes. Other suitable electrolytes include the chlorides, bromides and nitrates of the alkali metals. Other suitable organic materials which form insoluble lakes with the metal ions of the electrode can be used. Suitable electrode metals include chromium, copper, nickel and, preferably, iron.

In the above examples the Versenol 120, Sequestrene 30A, Cheelox B-14, Sequestrene Na-2, Nullapon Fe-12, and Perma Kleer OH are all chelates of the amino carboxylic acid type. Other amino carboxylic acids which may be used include di (hydroxyethyl) glycine and diethylenetriaminepentaacetic acid which latter compound is an effective chelate in both alkaline and acid solutions. The di (hydroxyethyl) glycine which is an amino monocarboxylic acid is less effective than the amino polycarboxylic acid chelates. The chelates according to this invention are preferably used in amounts which may vary from about 0.05% to about 1.0% pure chelate by weight of the total impregnating solution.

A support, preferably paper, is impregnated with any of the above solutions by passing it through a bath of the solution. Pressure rolls can be employed to remove excess. Recording paper having 40% by weight moisture is suitable. Treated paper is preferably stored in sealed containers until used.

It should be understood that this disclosure is for the purpose of illustration only and that the invention includes all equivalents and modifications falling within the scope of the appended claims.

I claim:

1. In an electrolytic facsimile recording medium for recording solely by passing a modulated electric current therethrough to form a colored mark with an organic marking compound contained therein, said medium consisting of a support impregnated with an electrolytically conductive solution consisting of an electrolyte and an organic marking compound producing color by chemical combination with metal electrode ions, the improvement which comprises including in said solution an amino polycarboxylic sequestering agent for said electrode metal ions in an amount sufficient to improve definition by complexing in colorless form recording metal electrode ions in non-recording parts of the support.

2. A recording medium according to claim 1 wherein said sequestering agent comprises from about 0.05 to about 1.0 percent by weight of said solution.

3. Electrolytic recording material according to claim 1

wherein said sequestering agent comprises a water soluble salt of ethylenediamine polyacetic acid.

4. Electrolytic recording material according to claim 1 wherein said sequestering agent comprises a water soluble salt of ethylenediaminetetraacetic acid.

5. Electrolytic recording material according to claim 1 wherein said sequestering agent comprises a water soluble salt of N-hydroxyethylmethylenediaminetriacetic acid.

6. A recording medium according to claim 1 wherein said marking compound is selected from the group consisting of methylene disalicylic acid, tannic acid, catechol and protocatechuric acid.

7. A recording medium according to claim 6 wherein said metal electrode ions comprise iron.

8. A recording medium according to claim 7 wherein said sequestering agent is selected from the group consisting of water soluble salts of EDTA, N-hydroxyethylmethylenediaminetriacetic acid, di(hydroxyethyl) glycine and diethylenetriaminepentaacetic acid.

9. Electrolytic recording material according to claim 1 which comprises a support impregnated with a water solution containing an electrolyte, methylene disalicylic acid, and a sequestering agent selected from the group which consists of soluble salts of N-hydroxyethylenediaminetriacetic acid and ethylenediamine tetraacetic acid.

10. Electrolytic recording material according to claim 1 which comprises a support impregnated with a water solution containing an electrolyte, a polyhydroxy phenol, and a sequestering agent selected from the group consisting of soluble salts of N-hydroxyethylenediaminetriacetic acid and ethylenediaminetetraacetic acid.
